UNITED STATES PATENT OFFICE.

JAMES A. CRUMLEY, OF CHARLESTON, WEST VIRGINIA, ASSIGNOR OF ONE-THIRD TO
ELVYN L. KELLER, OF CHARLESTON, WEST VIRGINIA.

PUMPING RIG.

Application filed June 27, 1923. Serial No. 647,960.

To all whom it may concern:

Be it known that I, JAMES A. CRUMLEY, a citizen of the United States, residing at Charleston, in the county of Kanawha and State of West Virginia, have invented certain new and useful Improvements in Pumping Rigs, of which the following is a specification.

This invention relates to improvements in foundations for rigs used in drilling and pumping wells.

The primary object of the invention is to generally simplify and improve devices of the above kind.

Another object of the invention is to construct rig foundations of pipe or structural steel whereby a simple and cheap structure is provided which will be of longer service than similar constructions now in use employing timber.

With the above general object in view, and others that will become apparent as the nature of the invention is better understood, the same consists in the novel form, combination and arrangement of parts herein-after more fully described, shown in the accompanying drawings and claimed.

In the drawings, wherein like reference characters indicate corresponding parts throughout the several views,

Figure 1 is a side elevational view of a rig foundation constructed in accordance with the present invention.

Figure 2 is an enlarged sectional view through the walking beam and taken substantially on line 2-2 of Figure 1.

Figure 3 is an end view of the walking beam.

Figure 4 is a view of one of the crank shaft supporting posts and adjacent parts, and

Figure 5 is an enlarged elevational view of the pitman.

Referring more in detail to the several views, the invention embodies a vertical supporting post 5 which is preferably in the nature of a piece of pipe with its lower end threaded in a base plate 6 which is suitably flanged and bolted as at 7 to a concrete foundation 8. A saddle box 9 is threaded

on to the upper end of the post 5 and embodies upper horizontally aligned split clamps 10 in which the ends of a shaft 11 are clamped, the clamps 10 being spaced apart to receive the saddle 12 of a walking beam 13 therebetween, which saddle embodies a lower portion in which the shaft 11 is freely movable for permitting free rocking of the walking beam, and inverted U-shaped clamps or bolts 14 which secure the saddle to the central portion of the walking beam. The walking beam 13 preferably consists of a length of pipe with upwardly directed end portions connected by a brace 15 which also consists in a smaller pipe section with its ends suitably secured as at 16 to the ends of the walking beam 13 as shown in Figure 1.

Directly beneath one end of the walking beam 13 there is provided a pair of short posts 17 which are preferably formed from sections of pipe and which have their lower ends threaded into a base plate 18 suitably bolted as at 19 to a concrete foundation 20. Suitable bearing caps 21, of split form, are threaded on the upper ends of the post 17, and the usual crank shaft 22 of the band wheel 23 is journaled in these bearings 21. It is to be understood that the band wheel 23 is disposed between the pair of posts 17, so that the latter are arranged in side by side spaced relation.

Each post 17 has the end of a brace 24 bolted to the same near the upper end thereof, the opposite ends of each brace 24 being suitably fastened as at 25 to the sill 26 of the derrick. The posts 17 are braced in the opposite direction by means of bumping poles 27 which are bolted to the posts 17 and are adapted to extend from the engine foundation, not shown. The braces 24 and 27 are preferably constructed of small pipe having their ends flattened so that they may be conveniently bolted to the posts 17 and sill 26, and this is also true with respect to a further brace 28 provided between the upper end portion of the walking beam supporting post 5 and the base 18 of one of the posts 17. Each end of the walking beam 13 is preferably longitudinally slotted as indicated at 28 in Figure 3, providing a pair of leg por-

tions each of which carry one of a pair of stirrup boxes 29 having split bearings for reception of the U-shaped stirrup 30 of a pitman 31, the pitman 31 having its central 5 portion preferably in the form of a section of pipe with the stirrup 30 secured on one end thereof by bolting or the like as at 32, and having a suitable journal box 33 fastened on the other end thereof for reception 10 of the crank portion of the shaft 22 or the like. It will be seen from the foregoing description that the various elements of the construction are, as a whole, mainly constructed as pipe sections with readily attachable parts so that a foundation of this 15 kind may be readily assembled at a cheap cost and in a small amount of time. Also, the device that is produced is efficient in operation and embodies strength and durability so that prolonged service is insured.

Minor changes may be made without departing from the spirit and scope of the invention as claimed.

What I claim as new is:

25 1. In a pumping rig for oil wells, the combination with the horizontal sill at the lower portion of a derrick, of a flanged base fixed at one side of and below said sill, a post mounted in said base, a saddle box fixed 30 upon the upper end of said post and including spaced clamps having a shaft fixed therein and extending therebetween, a saddle journaled upon said shaft, a walking beam, U-shaped bolts engaging the walking beam 35 and the saddle for clamping the latter together, a pair of spaced relatively short posts mounted adjacent the first named post in spaced relation and having bearing caps on the upper end thereof, a crank shaft 40 rotatable in said bearing caps, a pitman connected to the crank of said shaft and having a stirrup thereon, and a pair of cooperating stirrup boxes upon the end of the walking beam above the second named posts for reception 45 of the stirrup of said pitman adapted to connect the crank shaft with the walking beam.

2. In a pumping rig for oil wells, the combination with the horizontal sill at the lower portion of a derrick, of a flanged base fixed 50 at one side of and below said sill, a post mounted in said base, a saddle box fixed upon the upper end of said post and including spaced clamps having a shaft fixed 55 therein and extending therebetween, a saddle journaled upon said shaft, a walking beam, U-shaped bolts engaging the walking beam and the saddle for clamping the latter together, a pair of spaced relatively short posts 60 mounted adjacent the first named post in spaced relation, and having bearing caps on the upper end thereof, a crank shaft on a band wheel mounted in said bearing caps, a pitman connected at an end to the crank of

said shaft, and having a stirrup, and a pair 65 of cooperating stirrup boxes upon the end of the walking beam above the second named posts for the reception of the stirrup of said pitman adapted to connect the crank shaft with the walking beam, said post embodying 70 a pipe section threaded into the flanged base and on the upper end of which is threaded the saddle boxes and said walking beam having the bearing cap secured in the central portion thereof, for cooperation with 75 the saddle boxes in mounting said beam.

3. In a pumping rig for oil wells, the combination with the horizontal sill at the lower portion of the derrick, of a flanged base fixed at one side of and below said sill, a post mounted in said base, a saddle box fixed 80 upon the upper end of said post and including spaced clamps having a shaft fixed therein and extending therebetween, a saddle journaled upon said shaft, a walking beam, U-shaped bolts engaging the walking beam and the saddle for clamping the latter together, a pair of spaced relatively short posts 85 mounted adjacent the first named post in spaced relation and having bearing caps on the upper end thereof, a crank shaft on a band wheel rotatably mounted in the bearing caps between the last named posts, a pitman connected with the crank of said shaft and having a stirrup, and a pair of cooperating stirrup boxes upon the end of the walking beam above the second named post for reception of the stirrup of the pitman 90 adapted to connect the crank shaft with the walking beam, a tubular inclined brace between the base of one of the second named posts and the top of the first named post, a second inclined brace between the bottom sill of the derrick and each of said second 95 named posts, and oppositely extending bumping poles attached to the second named posts.

4. In a pumping rig for oil wells, the combination with the horizontal sill at the lower portion of a derrick, of a flanged base fixed 100 at one side of and below said sill, a post mounted in said base, a saddle box fixed upon the upper end of said post and including spaced clamps having a shaft fixed 105 therein and extending therebetween, a saddle journaled upon said shaft, a walking beam, U-shaped bolts engaging the walking beam and the saddle for clamping the latter together, a pair of spaced relatively short posts 110 mounted adjacent the first named post in spaced relation and having bearing caps upon the upper end thereof, a crank shaft on a band wheel rotatably mounted in the bearing caps between the last named posts, a pitman connected to the crank of said shaft having a stirrup on one end, and a pair of 115 cooperating stirrup boxes on the end of the walking beam above the second named posts, 120

for reception of the stirrup of the pitman adapted to connect the crank shaft with the walking beam, a tubular inclined brace between the base of one of the second named posts and the top of the first named post, a second inclined brace between the bottom sill of the derrick and each of said second named

posts, and oppositely extending bumping poles attached to the second named posts, said bumping poles and braces comprising 10 sections of pipe with flattened ends moulded to the members to which they attach.

In testimony whereof I affix my signature.

JAMES A. CRUMLEY.
